RACING GAME

Adolf Robins, White Plains, N. Y., assignor to
 Tip Top Toy Company, New York, N. Y., a
 copartnership consisting of Karl Tausig and
 Adolf Robins.

Application July 6, 1945, Serial No. 603,469

4 Claims. (Cl. 273—86)

1

The present invention is directed to game devices, more particularly to a game having competitive racing as its principal feature.

Games of this general character have long been known and used. Essentially they have consisted in a platform having thereon a set of figures such as of horses attached to cords or the like and the cords were wound on a suitable drum simultaneously to cause all the figures to move towards the end of the race course. Usually a single movement of the drum caused the movement of all of the participants of the race. In one such game, there was provided an oval track with grooves to guide the figures and the drum was in a container filled with irregular objects. It was intended that these objects would become entwined in the cords in various ways and thus cause irregular movements of the figures. Such an apparatus was very complicated and did not function very well. Each of the cords had to be provided with a separate drum and all of the drums were connected together. The drums were necessarily of different size. Also, the irregular objects did not function as desired to give an unpredictable result in the race.

The present invention is intended and adapted to overcome the difficulties and disadvantages inherent in prior structures and it has among its objects to provide a racing game which is simple in construction and which may be readily manipulated by even inexperienced operators.

It is also among the objects of the present invention to provide a compact apparatus in which all the elements may be retained when not in use and which may be readily transported and easily set up for use.

It is still further among the objects of the present invention to provide a game of the type described in which with each operation, the chances are so variable that it cannot be predicted until the very end of the race which of the figures will reach the finishing line first.

In practicing the present invention, there is provided a casing with a roller mounted horizontally therein and adapted to be rotated, usually by hand. A series of cords have one end secured to the roller and the other end to a figure or object such as a horse and rider, which is to participate in the race. The cord passes through a guide member which is a substantial distance below the level of the roller and adjacent thereto so that that portion of the cord which is between the guide and roller is in an inclined position near the vertical. Threaded onto each cord are one or more beads loosely strung on the cord.

2

In the operation of the game when the roller is being rotated to wind the cord thereon, the fibers of the cord making contact with the opening in the beads will tend to raise the same against the action of gravity. The relative forces are therefore opposed to each other, and depending upon chance, one or more of the beads will be raised into contact with the roller at unpredictable intervals. It depends considerably upon the character of the fibers which stand out from the cord, the relative diameters of cord and bead opening, the speed of rotation, and other variable factors. Once a bead contacts with the roller, then its cord is wound on the roller at a greater rate. This rate may vary amongst the several cords at various times due to the number of beads so contacting the roller and also the exact position of the bead on the roller.

As a result, one cannot predict with any certainty at all how the figures will finish a race. Even figures which have apparently a safe lead will in most cases lose a race. Very often a figure which has been in the rear of the contestants will finish first.

25 25 In the accompanying drawing constituting a part hereof, and in which like reference characters indicate like parts,

Fig. 1 is a perspective view of a casing containing the several elements of the racing game of 30 the present invention;

Fig. 2 is a vertical cross-sectional view taken along the line 2—2 of Fig. 1, some parts being shown broken away for clearness;

Fig. 3 is a vertical cross-sectional view similar 35 to that of Fig. 2, but showing the game in position for a race;

Fig. 4 is a horizontal cross-sectional view taken along the line 4—4 of Fig. 1, showing the several figures during the course of the race as they near 40 the finish line; and

Fig. 5 is a fragmentary vertical cross-sectional view showing some of the beads in contact with the roller during the course of a race.

45 The casing comprises a rear wall 1 and a pair of side walls 2 and 3, with a bottom member 4 and a top 5 permanently in position. A horizontal roller 6 is mounted between ends 2 and 3 of the casing, one end of the roller having a stop member 7 secured thereto and the other end having a crank 8 outside of the casing with a handle 9 for operating the same. A slide 10 operating in suitable grooves is adapted to close the casing. A knob 11 on slide 10 facilitates the introduction and removal thereof.

50 55 Within the casing is a vertical partition 12 sub-

stantially parallel to roller 14. In the bottom of partition 12 are a series of openings 13 constituting guides for the cords. Said openings are a substantial distance below roller 6 and but slightly displaced horizontally therefrom. One end of cords 14 is secured to roller 6 and the other end thereof is secured to object or figure 16. As shown more particularly in Figs. 3 and 5, a pair of beads 17 are threaded onto that section of cord 15 which lies between guide 13 and roller 6. The openings in beads 17 are somewhat larger than the diameter of cord 15 so as to fit loosely thereon.

Within the casing and on the opposite side of partition 12 from the section in which roller 6 is mounted, is a compartment 18. A plurality of vertical members constituting stalls 19 are fitted in compartment 18, the inner ends of said stalls making contact with partition 12. An incline or ramp 20 is provided at the open end or front of the casing. The stalls provide resting places for figures 16 when the device is not in use, as is shown in Fig. 2.

Although the invention has been described setting forth a single specific embodiment thereof, it will be apparent to those skilled in the art that various changes in the details of construction may be made therein. For instance, the casing need not be fully closed but one or more of the sides may be omitted. Compartment 18 is not absolutely essential and may be either entirely omitted or may be modified so that the several figures may be packed therein. Roller 6 need not be smooth or of a single diameter throughout its length but may be irregularly roughened and the diameter may be caused to vary in an irregular manner. While two beads have been shown on each cord, the number may vary and a single bead may be used, although preferably a larger number than shown, say three or four, may in many cases be preferable. The several beads on each cord may be of various sizes and shapes. The materials used in the construction may be changed at will to suit the occasion.

These and other changes in the details of construction may be made within the spirit of the invention, which is to be broadly construed and not to be limited except by the character of the claims appended hereto.

I claim:

1. A racing game comprising a casing, a roller mounted for horizontal rotation therein, a cord having one end secured to said roller, an object attached to the free end of said cord, a guide adjacent to said roller at a point substantially below said roller, said cord passing through said guide and upwardly onto said roller, at least one bead interposed between said guide and roller and loosely threaded on said cord, said bead during operation of said game being subjected to opposed forces of gravity and friction with said cord.

2. A racing game comprising a casing, a roller mounted for horizontal rotation therein, a plurality of cords having one end secured along said roller, an object attached to the free end of each cord, a vertical partition substantially parallel to said roller, a plurality of guides in said partition adjacent to said roller at a point substantially below said roller, said cords passing through said guides and upwardly onto said roller, at least one bead interposed between said guide and roller and loosely threaded on each cord, said bead during operation of said game being subjected to opposed forces of gravity and friction with said cord.

3. A racing game comprising a casing, a roller mounted for horizontal rotation therein, a plurality of cords having one end secured along said roller, an object attached to the free end of each cord, a vertical partition substantially parallel to said roller, a plurality of guides in said partition adjacent to said roller at a point substantially below said roller, said cords passing through said guides, a bead interposed between said guide and roller and loosely threaded on each cord, said bead during operation of said game being subjected to opposed forces of gravity and friction with said cord, a plurality of stalls adjacent said partition perpendicular thereto into which said objects may be fitted.

4. A racing game comprising a casing, a roller mounted for horizontal rotation therein, a plurality of cords having one end secured along said roller, an object attached to the free end of each cord, a vertical partition substantially parallel to said roller, a plurality of guides in said partition adjacent to said roller at a point substantially below said roller, said cords passing through said guides, a bead interposed between said guide and roller and loosely threaded on each cord, said bead during operation of said game being subjected to opposed forces of gravity and friction with said cord, a plurality of stalls adjacent said partition perpendicular thereto into which said objects may be fitted, and a slide fitted into said casing for enclosing said stalls.
